UNITED STATES PATENT OFFICE.

OLIVER M. BURTON, OF CHICAGO, ILLINOIS.

DESIGN FOR A MATTRESS.

43,449.

Specification for Design.

Patented Jan. 14, 1913.

Application filed September 30, 1912. Serial No. 723,261. Term of patent 14 years.

To all whom it may concern:

Be it known that I, OLIVER M. BURTON, a citizen of the United States, and a resident of Chicago, in the county of Cook and State of Illinois, have invented a new, original, and ornamental Design for a Mattress, of which the following is a specification, reference being had to the accompanying drawing, forming part thereof, in which—

mentary view, looking at the edge of the mattress; and Fig. 3 is a fragmentary perspective view of one corner of the mattress on a somewhat enlarged scale.

I claim:

The ornamental design for a mattress, as shown.

OLIVER M. BURTON.
